(57) **CLAIM**

The ornamental design for a lawn mower cleaner, as shown and described.

DESCRIPTION

FIG. 1 is a top perspective view of a lawn mower cleaner showing my new design.

FIG. 2 is a top view of the lawn mower cleaner of FIG. 1.

FIG. 3 is a left side view of the lawn mower cleaner of FIGS. 1 and 2, the right side view being a minor image thereof.

FIG. 4 is a bottom view of the lawn mower cleaner of FIGS. 1-3.

FIG. 5 is a rear end view of the lawn mower cleaner of FIGS. 1-4.

FIG. 6 is a front end view of the lawn mower cleaner of FIGS. 1-5.

FIG. 7 is a top perspective view of the lawn mower cleaner, wherein pipe threading is visible at the connections of the pipes to the fittings and nozzles of the cleaner.

FIG. 8 is a top view of the lawn mower cleaner of FIG. 7.

FIG. 9 is a left side view of the lawn mower cleaner of FIGS. 7 and 8, the right side view being a minor image thereof.

FIG. 10 is a bottom view of the lawn mower cleaner of FIGS. 7-9.

FIG. 11 is a rear end view of the lawn mower cleaner of FIGS. 7-10.

FIG. 12 is a front end view of the lawn mower cleaner of FIGS. 7-11; and,

FIG. 13 is a left side view of the lawn mower cleaner of FIGS. 1-6, wherein the environmental ground, lawn mower, hose portion, and water spray are shown in broken lines and are not part of the claimed design.
